[57] CLAIM

The ornamental design for a table, as shown and de-
scribed.

DESCRIPTION

FIG. 1 is a perspective view of a table showing my new
design;

FIG. 2 is a front elevational view thereof;

FIG. 3 is a top plan view thereof;

FIG. 4 is a left side elevational view as seen when in use;
and,

FIG. 5 is a right side elevational view as seen when in
use.

The rear of the table is flat and unornamented.
